(57) **CLAIM**

The ornamental design for an angled rotating grip, as shown and described.

DESCRIPTION

FIG. 1 is a front, right-side, bottom perspective view of the angled rotating grip showing my new design;

FIG. 2 is a front view, with the opposite side a mirror image thereof;

FIG. 3 is a right-side view thereof;

FIG. 4 is a left-side view thereof;

FIG. 5 is a bottom view thereof;

FIG. 6 is a perspective view of the rotating grip with the grip rotated at a different angle shown attached to a paddle.

FIG. 7 is a front view thereof with the angled grip rotated 45-degrees; and,

FIG. 8 is a perspective view of two angled rotating grips with the grips rotated at different angles and attached to paddles showing one intended use.

The broken lines shown FIG. 6, illustrate environmental structure that form no part of the claimed design.
